UNITED STATES PATENT OFFICE.

HENRY C. FABER, OF UTICA, NEW YORK.

TRUNK.

SPECIFICATION forming part of Letters Patent No. 284,197, dated September 4, 1883.

Application filed June 13, 1883. (No model.)

To all whom it may concern:

Be it known that I, HENRY C. FABER, of the city of Utica, county of Oneida and State of New York, have invented and discovered 5 a new and useful Improvement in Trunks, of which the following is a specification.

My invention relates to improvements in the method of constructing trunks to enable them more easily to withstand the hard usage which 10 is consequent in traveling, and to obtain a greater quality of strength and lightness combined.

In the accompanying drawings, Figure 1 represents a perspective view of a trunk constructed according to the specifications. Fig. 15 2 represents a side view of a top corner-guard. Fig. 3 represents a front view of the same. Fig. 4 represents a front view of an angular guard placed to protect the top corners of the 20 trunk proper from the concussions made by the closing of the cover, and to form a solid basis for the cover to rest upon. Fig. 5 represents a top view of the same. Fig. 6 represents a side view of a guard placed on the bottom 25 corners of the trunk, showing the curvature. Fig. 7 represents a bottom view of the same. Fig. 8 represents an inside side view of the same. Fig. 9 represents a section of part of the trunk, showing the combination of 30 wood, glue, and canvas.

Similar letters refer to similar parts throughout the several views.

The nature and construction of my invention consists in a trunk, made of wood, with 35 smooth surfaces, to which canvas is glued. The canvas is put quickly on both the inside and outside of the wood with hot glue, and then smoothed over, so as to be wholly free from roughness. This combination gives the wood 40 a very elastic and tenacious quality, which enables it to be bent to a considerable degree without injury, the wood being made perfectly smooth, so that the canvas, in combination with the glue, may fit tightly and snugly, and communicate to the wood in the combination the 45 characteristics of elasticity and durability. The outside canvas is painted or prepared to protect the trunk and contents from moisture and water, and also to make the same more 50 durable. Along the lengthwise edges of the top of the cover and bottom of the trunk are strips, or sections of strips, of pressed raw-

hide, fastened partly by means of rivets, and partly by nails, which are clinched on the inside. These strips, running with the grain of 55 the wood, are scalloped or cut so as not to make a straight line on the edge and form a wedge to crack the wood, and can be extended any required distance over both sides of the edges to suit the taste of the person making 60 the trunk. Straight strips are placed and fastened in a like manner along both the top and bottom edges made by the intersection of the narrow sides and the top and bottom of the trunk. A pad of pressed rawhide, which overlaps and covers the aforesaid strips, making a double thickness, is placed and fastened in the manner stated on each of the eight corners of the trunk, as indicated in Fig. 1. Around the 65 trunk, crosswise to the length of the same, are fastened in like manner strips of rawhide, the sections of which strips are so arranged as to overlap each other on the several edges of the trunk, making a double thickness, and similar strips extend up the two narrow sides of the 70 trunk. The number of these strips can be increased or diminished without interfering with my invention. Between the strips which extend around the trunk crosswise to its length are placed, both on the top and sides of the trunk, 75 short strips of rawhide, which are fastened, as before stated, and also across the four side edges of the trunk, fastened in like manner, are short strips of rawhide, which extend a suitable distance over both sides, and form a double 80 thickness by overlapping the strips which extend down the side edges of the trunk, as indicated in Fig. 1. The raw-hide is so prepared as to be wholly impervious to water. The nails and rivets with which the several pieces of pressed 85 rawhide are secured extend, with a rounded or beveled surface, a sufficient distance above the rawhide to aid in protecting the same from rubbing against anything; but this projection may be omitted without interfering with the 90 usefulness of my invention. As a further security, guards or protectors are fastened on the four top corners of the cover of the trunk. The guards are constructed of brass or any 95 suitable metal, and consist of a bulb-head, with three arms of equal length extending from the head, as indicated in Figs. 2 and 3, and are firmly secured by means of rivets at the ends 100 of the arms. On each of the four top corners

of the trunk proper is inserted and riveted a
 5 guard, angular, made of brass or any suitable
 metal, in such a manner as to closely fit the
 cover of the trunk when closed. A metal
 band, which extends around the bottom of the
 cover of the trunk and holds the same firmly
 together, keeping the edges from splitting or
 spreading, overlaps the upper part of this an-
 gular guard and strikes or rests upon a right-
 10 angle projection or shoulder of the same. This
 arrangement allows the cover to be closed with
 any reasonable force without injury to the
 trunk or any part thereof. The cover is snugly
 fitted to the guards, which serve as a solid
 15 basis for the same, and serve to make, when
 the cover is closed, a solid and firm structure.
 The bottom corners of the trunk are protected
 by means of guards made of any suitable metal,
 and are arranged on the trunk, as indicated
 20 by D in Fig. 1. This guard consists of three
 plates, formed as indicated in Figs. 6, 7, and
 8, and are securely fastened to the trunk by
 rivets at the end of the plates. The guards
 are both right and left. The lower part of the
 25 front plate and the bottom plate incase the
 slat on the bottom of the trunk. Then the
 front plate curves outward, so as to protect
 the corner-pads, as indicated in Fig. 6. The
 plates of the guard do not project out straight
 30 from the base, but curve sufficiently, so as to
 wholly protect the corners, which are neces-
 sarily made rounding by the corner-pads, the
 rounding surface being much more secure from
 injury than if the plates came to a point.
 35 Having described the nature and construc-
 tion of my invention, I will now describe it
 with reference to the accompanying drawings,
 in which A represents the trunk. B repre-
 sents the guard placed on the top corners of
 40 the cover. C represents the angular guard,
 placed on the top corners of the trunk proper,
 the upper part of which the cover of the trunk
 overlaps, and rests, when closed, upon the
 shoulder g. D represents the guard placed on
 45 the bottom corners of the trunk. E represents

a section of the trunk, showing the combina-
 tion of the wood, glue, and canvas. a repre-
 sents the pad placed on the top corners, so as
 to overlap the strips b and e. a' represents a
 similar pad placed on the bottom corners of
 50 the trunk. b represents the scalloped strips
 or sections of strips fastened along the edges
 of the cover, running lengthwise to the trunk.
 b' represents similar strips along the bottom
 edges of the trunk. c represents the short
 55 strips of rawhide riveted across the four side
 edges of the trunk, overlapping the strips fast-
 ened along the side edges. d and d' represent
 side sections of the strips, which extend around
 and up the two narrow sides of the trunk. e
 60 represents top sections of the same. f and f'
 represent the strips which are placed and fast-
 ened between the sections d d' and e of the
 strips which extend around the trunk. g repre-
 65 sents the shoulder of guard C, upon which
 the iron band on the cover strikes or rests
 when closed. h represents the wood in the
 combination, and i represents the canvas in
 the combination.

What I claim as my invention and discov-
 ery, and which I desire to secure by Letters
 Patent, is—

1. The trunk-body A, constructed of wood h, glue, and canvas i i, in combination with the strips and sections of pressed and prepared 75 rawhide b, b', c, d, d', and e, and also pads a and a', as and for the purposes stated.
2. The trunk-body A, constructed of wood h, glue, and canvas i i, and with the strips and sections of pressed and prepared rawhide b, b', 80 c, d, d', e, f, and f', provided with pads a and a', in combination with guards B, C, and D, as and for the purposes specified.

Signed at Utica, in the county of Oneida and
 State of New York.

HENRY C. FABER.
